UNITED STATES PATENT OFFICE.

CLIFFORD J. WILLIAMS, OF DETROIT, MICHIGAN, ASSIGNOR TO BRIGGS MANUFACTURING COMPANY, OF DETROIT, MICHIGAN, A CORPORATION OF MICHIGAN.

ADJUSTABLE STRIKER PLATE.

Application filed February 9, 1925. Serial No. 8,045.

This invention relates generally to striker plates designed particularly for use in connection with the spring pressed bolts of vehicle door locks and latches and consists 5 of certain novel features of construction, combinations and arrangements of parts as will be more fully described and particularly pointed out in the appended claims.

In the accompanying drawing:

10 Figure 1 is a fragmentary side elevation of a door jamb with the striker plates embodying my invention attached thereto.

Figure 2 is a cross sectional view taken on the line 2—2 of Figure 1.

15 Figure 3 is a perspective view of the retainer plate with the channel shaped housing attached thereto.

Figure 4 is a detail perspective view of the channel shaped housing.

20 Figure 5 is a detail plan view of the square shaped bearing plate.

Figure 6 is a section on the line 6—6 of Figure 1.

Referring now to the drawing in which 25 like characters of reference designate corresponding parts throughout the several views, the numeral 1 designates a door jamb preferably of a vehicle body, formed of two sheet metal stampings 2 and 3 respectively.

30 As shown, the stamping 2 is preferably channel shaped and is provided at its forward edge with a laterally extending flange 4, while the stamping 3 is also preferably channel shaped in cross section and has one 35 flange 5 thereof overlapping the lateral flange 4 of the stamping 2. These overlapping flanges may be secured together by any suitable means.

40 In order that a swinging door 6 may be held partially closed or fully closed with respect to the jamb 1, I preferably provide two striker plates 7 and 8 respectively that are arranged in tandem upon the door jamb and are adapted to be engaged by the movable bolt 9 of a lock carried by the door.

45 The striker plate 7 is preferably formed of sheet metal and is preferably permanently secured to the jamb section 3, while the striker plate 8 is also preferably formed of sheet metal but is preferably adjustable transversely of the section 2 for taking up 50 wear and preventing the bolt 9 from rattling. As shown, the striker plate 7 is preferably wedge-shape in form and is provided at its opposite sides with laterally extending

attaching ears 10 which are preferably screwed to the flange 5 of the jamb section 3. The striker plate 8 is also preferably wedge-shape in form but is preferably movable longitudinally of an elongated opening 60 11 that extends transversely of the jamb section 2 from the inner edge of the lateral flange 4 to a point adjacent to the rear flange 12. For supporting the striker plate 8 in the opening 11, I preferably provide a channel-shaped retainer plate 13 that extends transversely of the jamb and is provided with laterally extending flanges 14 that are rigidly secured to the jamb section 2 upon opposite sides of the opening 11. As shown, this channel retainer plate is preferably square shaped and is adapted to receive a correspondingly shaped plate 15 upon which the striker plate 8 is preferably mounted. For retaining the striker plate 8 in position upon the plate 15, I preferably provide a suitable screw 16 that extends freely through circular openings 17, 18 and 19 respectively in the striker plate 8, square plate 15 and base 20 of the retainer plate 13 and threadedly engages a nut 21 located within a channel-shaped housing 22 that is secured to the base of the retainer plate 13. As shown, the opening 18 is preferably off-set from the centre of the plate 15 and is adapted to register with any one of the openings 19 which are preferably spaced equi-distant from the centre of the channel-shaped base 20 of the retainer plate. Hence the striker plate 8 may be adjusted transversely of the jamb by first disengaging the screw 16 from the nut 21 and retainer plate 13, and subsequently removing the latter from the channel. This plate 15 is then turned ninety degrees, one hundred and eighty degrees, 85 etc., as desired so that the opening 18 therein will register with another opening 19 in the base of the retainer plate 13, whereupon the square plate 15 may be replaced in the channel of the retainer plate and the screw 16 90 may be engaged with the nut 21 to hold the parts in adjusted position. Inasmuch as the striker plate 8 is mounted freely upon the square plate 15, it will be readily apparent that the latter may be turned as desired 105 without turning the striker plate 8. Moreover, the arrangement of the openings 19 and the location thereof with respect to the forward edge of the retainer plate 13 is such that these openings may be alternately 110

engaged by the screw 16 to adjust the striker plate 8 to four different positions transversely of the jamb. Any number of openings 19 may be provided as may be found necessary.

If desired, the base 23 of the channel-shaped housing 22 may be provided with a longitudinally extending slot 24 to accommodate the free end of the screw 16. The 10 opposite ends of the channel-shaped housing 22 may also be closed by flanges 25 which are turned inwardly from the base 23 of the housing to prevent any accidental displacement of the nut 21.

15 From the foregoing description it will be readily apparent that the striker plates 7 and 8 respectively may be alternately engaged by the bolt of the door lock for holding the door in either partially closed position or in fully closed position with respect to the door jamb. Inasmuch as the striker plates 7 and 8 are formed of sheet metal, it is readily apparent that the cost of manufacturing such devices has been reduced to a 20 minimum. Moreover, the arrangement is such that the parts may be easily and quickly assembled or taken apart whenever desired.

25 While it is believed from the foregoing 30 description that the nature and advantages of the invention will be readily apparent, yet I desire it understood that I do not limit myself to what is herein shown and that such changes may be resorted to when desired as fall within the scope of what is claimed.

What I claim as my invention is:

1. A device of the class described including a supporting member having a plurality 40 of openings therein, a striker plate adjustable transversely of said member, an intermediate plate having a single opening off-set from the center thereof adapted to register alternately with said openings, and means for mounting the striker plate including an element extending transversely of 45 said striker plate and engageable with said registering openings.

2. A device of the class described, a 50 square-shaped retainer plate, a striker plate adjustable transversely thereof, means for mounting the striker plate including a member extending transversely of the striker plate, said retainer plate having a plurality 55 of openings spaced equi-distant to the centre thereof alternately engageable by said member.

3. A device of the class described including a retainer plate having a plurality of 60 openings spaced equi-distant to the centre, a

striker plate adjustably mounted on said retainer plate, an intermediate plate having a single opening off-set from the centre thereof and adapted to alternately register with the openings in the retainer plate, and a 65 headed element extending through said retainer plate and intermediate plate.

4. A device of the class described including a channel-shaped retainer plate having a plurality of openings therein, a striker 70 plate adjustable transversely of said retainer plate, means for mounting the striker plate including a screw extending transversely of said striker plate and alternately engageable with said openings, a nut threadedly engaging the screw upon the inner side of the retainer plate for holding the striker plate in position and a housing for the nut carried by the retainer plate. 75

5. A device of the class described comprising a retainer plate having a plurality of openings therein, a striker plate adjustable transversely of said retainer plate, means for mounting the striker plate including a screw extending transversely of said striker 80 plate and alternately engageable with said openings, a nut threadedly engaging the screw upon the inner side of the retainer plate for holding the striker plate in position, and a channel-shaped housing for the 85 nut extending transversely of the supporting member secured to the retainer plate and having means for preventing accidental displacement of the nut. 90

6. A device of the class described including a retainer plate having a plurality of openings therein, a striker plate adjustable transversely of the retainer plate, means for mounting the striker plate including a member extending transversely of said striker plate and alternately engageable with said 100 openings, and intermediate plate having an opening off-set from the centre thereof receiving said member, and an element adjustably engaging said member upon the inner side of the retainer plate for holding the striker plate in position. 105

7. A device of the class described including a channel-shaped retainer plate, having a plurality of openings therein, a wedge-shaped striker plate adjustable transversely of the retainer plate having a depression in the inclined wall thereof, and means for mounting the striker plate including a headed element extending through the depressed portion of said striker plate and adapted to alternately engage the openings in said retainer plate. 110 115

In testimony whereof I affix my signature.
CLIFFORD J. WILLIAMS.
